UNITED STATES PATENT OFFICE.

HERMAN M. HOELSCHER AND JOHN J. CLIFFORD, OF CHICAGO, ILLINOIS,
ASSIGNORS TO L. WOLFF MANUFACTURING COMPANY, OF CHICAGO,
ILLINOIS, A CORPORATION OF ILLINOIS.

NON-SCALDING SHOWER-BATH COCK.

No. 825,214.

Specification of Letters Patent.

Patented July 3, 1906.

Application filed October 19, 1905. Serial No. 283,465.

To all whom it may concern:

Be it known that we, HERMAN M. HOELSCHER, and JOHN J. CLIFFORD, citizens of the United States, residing in Chicago, in the county of Cook and State of Illinois, have invented a new and useful Improvement in Non-Scalding Shower-Bath Cocks, of which the following is a specification.

Our invention relates to improvements in non-scalding shower-bath cocks.

The object of our invention is to provide a non-scalding shower-bath cock of a simple, efficient, and durable construction for controlling the flow of hot or cold water and hot and cold water mixed to a shower-bath or its connection-pipe, which will be simple in operation and capable of being readily manipulated by children and other persons having little or no familiarity with shower-baths and without possibility of hot water being suddenly turned on, and thus scalding, endangering, or injuring the person.

Our invention consists in the means we employ to practically accomplish this object or result—that is to say, it consists in a three-way-valve shell or case furnished with one nipple connecting with the hot-water-supply pipe, a second nipple connecting with the cold-water pipe, and a third nipple connecting with the shower-connection pipe, valve-seats and valves for opening and closing the communications with each of said pipes, a non-rotatable reciprocating sleeve carrying the shower-connection valve and provided with cams or inclines adapted to engage and open first the cold-water valve, afterward by further movement to open the hot-water valve, and then by still further movement to close or permit the closing of the cold-water valve and leave the hot-water valve open, and a rotary screw-stem extending through and carrying said non-rotatable-valve-operating sleeve, whereby one turn or partial turn of the screw-stem will first open the shower-connection valve and the cold-water valve and further turning of the screw-stem will then open the hot-water valve and maintain the cold-water valve also open, thus delivering cold and hot water mixed to the shower, the relative proportions of hot and cold water being varied as required by turning the screw-stem more or less, and still further turning of the screw-stem will close or permit the clos-

ing of the cold-water valve, and thus cause hot water only to be delivered to the shower, so that the hot water cannot be turned on at all without first turning on the cold water and so that hot water only cannot be delivered to the shower at all without first delivering hot and cold water mixed and gradually diminishing and finally cutting off the cold-water supply, and thus practically removing all danger of scalding or injury, however ignorant or unskilled the person may be in the manipulation of the shower.

Our invention also consists in the novel construction of parts and devices and in the novel combinations of parts and devices herein shown and described.

In the accompanying drawings, forming a part of this specification, Figure 1 is a central vertical section of a non-scalding shower-cock embodying our invention. Fig. 2 is a vertical section on line 2 2 of Fig. 1. Fig. 3 is a horizontal section on line 3 3 of Fig. 2. Fig. 4 is a section on line 4 4 of Fig. 2. Fig. 5 is a detail view of the non-rotatable reciprocating valve-operating sleeve, and Fig. 6 is a detail end view of said sleeve.

In the drawings, A represents the main shell or case of the cock, the same having a screw-threaded nipple A' for connection with the hot-water-supply pipe B and a screw-threaded nipple A² for connection with the cold-water-supply pipe C, and a nipple A³ for connection with the shower pipe or connection D. The valve-shell A is furnished with a valve-seat a for the discharge or shower-connection valve E, a valve-seat a' for the cold-water valve F, a valve-seat a² for the hot-water valve G, and also with integral webs a³ a⁴, having holes therethrough for guiding and supporting the valve-stems f g of the valves F G. The valves F G open against the water-pressure, and their stems f g are preferably furnished with springs f' g', bearing against the shoulders or collars f² g² on the valve-stems to aid the water-pressure in holding the valves normally closed.

H is a non-rotatable reciprocating valve-operating sleeve, the same carrying the discharge shower-connection valve E directly thereon and being preferably provided with an annular flange h to receive said shower or discharge valve E. The non-rotating reciprocating sleeve H is provided with a cam or in-

cline h' , adapted to engage the stem of the cold-water valve and open the same, and a reverse incline h^2 for gradually closing or permitting the gradual closing of the cold-water valve by the further reciprocating movement of the sleeve H. The sleeve H is further provided with a cam or incline h^3 , adapted to engage the stem of the hot-water valve and open the same, the incline h^3 beginning at a point beyond the beginning of the cold-water-valve-opening incline h' , so that the hot-water valve will not be open until after the cold-water valve has been first opened. The hot-water-valve-operating incline or cam h^3 extends beyond the cold-water-opening incline h' , so that the hot-water valve may be kept open by said incline h^3 after the cold-water valve is permitted to become closed by the reverse incline h^2 . The non-rotatable reciprocating sleeve H is mounted upon a rotatable screw-stem K and is caused to reciprocate and move with the screw-stem by collars or shoulders k k' thereon and is prevented from turning with the screw-stem by guide-flanges h^4 h^5 on the sleeve H, which engages a guide pin or screw M, fixed to the main case or shell A. The screw-stem K is preferably hollow and furnished with internal screw-threads which engage a stationary screw P, fixed to the shell A, which is furnished with a screw-threaded boss A', the threads of which engage the screw-threads p on the head P' of the screw P. The screw-stem K is furnished with a knob or handle K' for turning the same, and it extends through a screw-threaded cap R, secured to the screw-threaded rim or nipple A⁶ of the shell A. The cap R is furnished with a stuffing-box R', having packing r to afford a watertight connection between the rotating and reciprocating screw-stem K and the cap R of the shell A. The shell A is also preferably provided with a screw-threaded nipple A⁶ to receive the screw-threaded end of the drip-cock S. The cams or inclines h' and h^3 and reverse incline h^2 on the valve-operating reciprocating sleeve H are preferably so located and arranged in relation to each other and in relation to the pitch of the threads on the screw-stem K that one turn of the screw-stem will turn on the cold water, two further turns will deliver hot and cold water mixed in substantially equal proportions, and two still further turns will cause hot water only to be delivered or supplied to the shower.

We claim—

1. In a non-scalding shower-bath cock, the combination with a valve shell or case having connections for the hot-water pipe, cold-water pipe, and the pipe leading to the shower, and provided with valve-seats for the hot water, cold water and shower controlling valves, of a hot-water valve, a cold-water valve, and a shower-valve, a non-rotatable reciprocating sleeve carrying the

shower-controlling valve and provided with a cam or incline for opening the hot-water valve, and a second cam or incline in advance of said hot-water-valve-operating incline for operating and opening the cold-water valve before the hot-water valve is opened, said cam or incline for opening the cold-water valve having a reverse incline to permit the cold-water valve to close while the hot-water valve is held open, a rotating screw-stem for reciprocating said sleeve, and a stationary screw secured to the valve-shell coöperating with said screw-stem, said reciprocating sleeve being provided with guides or flanges, and said valve-shell having a guide-pin engaging said guides on said sleeve to prevent the sleeve from turning, substantially as specified.

2. In a non-scalding shower-bath cock, the combination with a valve-shell, of a hot-water valve, a cold-water valve, a non-rotatable reciprocating sleeve provided with cams or inclines thereon engaging the stems of said valves for operating the same, the cam or incline for operating the cold-water valve being in advance of the one for operating the hot-water valve, and having a reverse incline to permit the closing of the cold-water valve after the hot-water valve has been opened, and a screw-stem for reciprocating said sleeve whereby cold water is first delivered, then cold and hot water mixed, and hot water can only be delivered alone after first turning on and off the cold water, substantially as specified.

3. In a non-scalding shower-bath cock, the combination with a valve-shell, of a hot-water valve, a cold-water valve, a non-rotatable reciprocating sleeve provided with cams or inclines thereon engaging the stems of said valves for operating the same, the cam or incline for operating the cold-water valve being in advance of the one for operating the hot-water valve, and having a reverse incline to permit the closing of the cold-water valve after the hot-water valve has been opened, a screw-stem for reciprocating said sleeve whereby cold water is first delivered, then cold and hot water mixed, and hot water can only be delivered alone after first turning on and off the cold water, and a stationary screw secured to the valve-shell and coöperating with said screw-stem, substantially as specified.

4. In a non-scalding shower-bath cock, the combination with a valve-shell, of a hot-water valve, a cold-water valve, a non-rotatable reciprocating sleeve provided with cams or inclines thereon engaging the stems of said valves for operating the same, the cam or incline for operating the cold-water valve being in advance of the one for operating the hot-water valve, and having a reverse incline to permit the closing of the cold-water valve after the hot-water valve has been opened.

- opened, and a screw-stem for reciprocating said sleeve whereby cold water is first delivered, then cold and hot water mixed, and hot water can only be delivered alone after first turning on and off the cold water, said reciprocating sleeve having guides or flanges thereon, and the valve-shell having a guide-pin engaging said guide-flanges on the sleeve to prevent the sleeve from turning, substantially as specified.
5. In a non-scalding shower-bath cock, the combination with a valve-shell, of a hot-water valve, a cold-water valve, a non-rotatable reciprocating sleeve provided with cams or inclines thereon engaging the stems of said valves for operating the same, the cam or incline for operating the cold-water valve being in advance of the one for operating the hot-water valve, and having a reverse 15 incline to permit the closing of the cold-water valve after the hot-water valve has been opened, and a screw-stem for reciprocating said sleeve whereby cold water is first delivered, then cold and hot water mixed, and hot 20 water can only be delivered alone after first turning on and off the cold water, and a shower-controlling valve operated by said reciprocating sleeve, substantially as specified.
- 25 6. In a non-scalding shower-bath cock, the combination with a valve-shell, of a reciprocating hot-water valve, a reciprocating cold-water valve, and a non-rotatable sleeve reciprocating between and at right angles to said hot and cold water valves and provided with cams or inclines thereon engaging the stems of said valves for operating the same, the cam or incline for the cold-water valve opening said valve before the hot-water 30 valve is opened, and a screw-stem for reciprocating said sleeve, substantially as specified.
- 35 7. In a non-scalding shower-bath cock, the combination with a valve-shell, of a reciprocating hot-water valve, a reciprocating cold-water valve, and a non-rotatable sleeve reciprocating between and at right angles to said hot and cold water valves and provided with cams or inclines thereon engaging the 40 stems of said valves for operating the same, the cam or incline for operating the cold-water valve opening said valve before the hot-water valve is opened, and a screw-stem for reciprocating said sleeve, substantially as specified.
- 45 8. In a non-scalding shower-bath cock, the combination with a valve-shell, of a reciprocating hot-water valve, a reciprocating cold-water valve, and a non-rotatable sleeve reciprocating between and at right angles to said hot and cold water valves and provided with cams or inclines thereon engaging the 50 stems of said valves for operating the same, the cam or incline for operating the cold-water valve opening said valve before the hot-water valve is opened, and a screw-stem for reciprocating said sleeve, and means for preventing said sleeve from turning, substantially as specified.
- 55 9. A non-scalding cock, comprising in combination a valve-shell, a hot-water-supply valve, a cold-water-supply valve, a reciprocating slide carrying the discharge-valve and provided with cams or inclines for operating the cold and hot water valves in succession, and a rotary screw-stem for reciprocating said valve-operating slide, substantially as specified.
- 60 10. A non-scalding cock, comprising in combination a valve-shell, a hot-water-supply valve, a cold-water-supply valve, a reciprocating slide carrying the discharge-valve and provided with cams or inclines for operating the cold and hot water valves in succession, a rotary screw-stem for reciprocating said valve-operating slide, and a stationary screw secured to the valve-shell and engaging said rotary screw-stem, substantially as specified.
- 65 11. A non-scalding cock, comprising in combination a valve-shell, a hot-water-supply valve, a cold-water-supply valve, a reciprocating slide carrying the discharge-valve and provided with cams or inclines for operating the cold and hot water valves in succession, and a rotary screw-stem for reciprocating said valve-operating slide, the cam or incline for opening the cold-water valve having a reverse incline to permit the closing of the cold-water valve and by further turns of the screw-stem in the same direction and thus delivering hot water only after the cold water has been turned off, substantially as specified.
- 70 12. A non-scalding cock, comprising in combination a valve-shell, a hot-water-supply valve, a cold-water-supply valve, a reciprocating slide carrying the discharge-valve and provided with cams or inclines for operating the cold and hot water valves in succession, a rotary screw-stem for reciprocating said valve-operating slide, and a stationary screw secured to the valve-shell and engaging said rotary screw-stem, the cam or incline for opening the cold-water valve having a reverse incline to permit the closing of the cold-water valve and by further turns of the screw-stem in the same direction and thus delivering hot water only after the cold water has been turned off, substantially as specified.
